RATCHET AND PAWL MECHANISM

Fred Waller, Huntington, N. Y., assignor to The
Vitarama Corporation, Long Island City, N. Y.,
a corporation of New York

Application December 9, 1943, Serial No. 513,616

10 Claims.

(Cl. 74—142)

This invention relates to ratchet and pawl mechanisms.

It is an object of the invention to provide a ratchet and pawl mechanism which may be operated at high speed, accurately and without overthrow, and which is adapted to operate satisfactorily both for movements of relatively small and relatively large amplitude.

Other objects and advantages of the invention will appear hereinafter.

A preferred embodiment of the invention selected for purposes of illustration is shown in the accompanying drawing, in which,

Figure 1 is a top plan view of the mechanism.

Figure 2 is a front elevation, and

Figure 3 is a front elevation of a modified form.

Referring to Figures 1 and 2, the invention is illustrated as applied to a ratchet wheel 1 which is rotatably mounted on a shaft 2, and in which the ratchet teeth 3 are closely spaced, as for example, in which the teeth are spaced at .02" or less.

The feed pawl 4 is pivoted at 5 on an idler member 6 which is mounted to move in a path such that the pivot 5 is always equally spaced from the toothed rim of the ratchet wheel. Thus, in the embodiment illustrated, the member 6 is pivoted on the shaft 2, but the member 6 should be so mounted as to have slight frictional resistance to movement in either direction.

The pawl is provided with a lever arm 7 extending substantially at right angles to the pawl, and the lever arm is connected in any suitable manner with suitable actuating means such as the armature 8 of the solenoid 9. The lever arm 7 is also connected to a spring 10 adapted to return the pawl to normal position after actuation, and carries a pin 11 positioned to engage the idler member 6 to return said member to normal position after actuation.

A holding detent 12 is also provided, said detent being mounted on a member 13 having a curved cam surface 14 concentric with the toothed rim of the ratchet wheel. The member 13 is mounted to move outwardly to release the detent. The movement of the member 13 required to release the detent is small and does not substantially alter the concentric relationship between the cam surface and the rim of the ratchet wheel, but if desired the cam surface may be formed so as to be concentric with the rim of the ratchet wheel when the member 13 is in raised position, as it is in this position that the cam surface is utilized as herein-after explained. The member 13 may be mounted

in any suitable manner, but in the embodiment illustrated is provided with a relatively long arm 15 which is pivotally mounted at 16. The member 13 and detent are normally held in engagement with the ratchet wheel by the spring 17.

The pawl is also provided with a lever arm 18 having a pin 19 mounted to cooperate with the cam surface 14. Thus, when the solenoid is energized because of the slight frictional resistance to movement of the idler member 6, the initial forward movement of the lever arm 7 causes the pawl to pivot on the idler member 6 to engage a tooth of the ratchet wheel, and causes the lever arm 18 to lift the member 13 and the detent 12 to free the ratchet wheel. Subsequent forward movement of the lever arm 7 causes the idler member 6 to advance with the pawl, which remains in engagement with the ratchet tooth, thus advancing the ratchet wheel. At the same time, the pin 19, riding along the concentric cam surface 14 retains the detent out of engagement with the ratchet wheel.

When the solenoid is deenergized, the initial backward movement of the lever arm 7 under the influence of the spring 10 causes the pawl to pivot on the idler member 6 to lift the pawl out of engagement with the ratchet wheel, and causes the lever arm 18 to move downwardly, allowing the member 13 and detent to move downwardly under the influence of the spring 17 to re-engage the ratchet wheel. Subsequent backward movement of the lever arm causes the pin 11 to engage the idler member 6 to return it to its initial position.

It will be observed that the pawl must be fully engaged with the ratchet wheel before any advancing movement can take place. Likewise the advancing movement must have ceased before the pawl can be released from the ratchet wheel. Furthermore, the arrangement of the parts is such that on the advancing stroke the detent is not released from the ratchet wheel until the pawl is in engagement therewith, and on the return stroke the pawl is not released from the ratchet when until the detent is in engagement therewith.

Means may be provided to limit the amplitude of movement of the idler member, and in consequence the amplitude of movement of the pawl, such means comprising, in the embodiment illustrated a limit stop 20 pivoted at 21 so that it may be moved into or out of position to limit the movement. In the embodiment illustrated the limit stop is set to permit the ratchet wheel to be advanced one tooth at a time, but it will be understood that other settings may be made.

In the embodiment illustrated in Figures 1 and 2 the mechanism is adapted for two way operation, that is, to rotate the ratchet wheel in clockwise or counter-clockwise direction. Thus, the pawl 4' and idler 6' are provided and the member 13 is extended at 13' to provide a cam surface 14'. The pawl is provided with lever arms 7' and 18' and said arms are provided with pins 11' and 19', all of said parts functioning as their counterparts previously described. The spring 10 is also connected to the arm 7' so that when the arm 7 is moved the arm 7' serves as a fixed support for the other end of the spring and vice versa.

In Figure 3, the invention is illustrated as adapted for use in connection with a straight ratchet bar 31 having ratchet teeth 33. A feed pawl 34 is pivoted at 35 on an idler slide 36 having slots 50 allowing the desired amplitude of longitudinal motion on the guide pins 51. The motion of the slide, of course, is parallel to the motion of the ratchet bar, but the slide should be so mounted as to have slight frictional resistance to movement.

The pawl is provided with a lever arm 37 extending substantially at right angles to the pawl, and the lever arm is connected in any suitable manner with suitable actuating means such as the armature 38 of the solenoid 39. The lever arm 37 is also connected to a spring 40 adapted to return the pawl to normal position after actuation, which said spring may also serve to return the slide.

A holding detent 42 is also provided, said detent being mounted on a member 43 having a cam surface 44 parallel to the toothed edge of the ratchet bar. The member 43 is slidably mounted to move vertically to release the detent, being provided for this purpose with slots 45 engaging guide pins 46. The member 43 and detent 42 are normally held in engagement with the ratchet bar by the spring 47.

The pawl is also provided with a lever arm 48 having a pin 49 mounted to cooperate with the cam surface 44. Thus when the solenoid is energized, because of the slight frictional resistance to movement of the slide 36, the initial forward movement of the lever arm 37 causes the pawl to pivot on the idler slide 36 to engage a tooth of the ratchet bar and causes the pin 49 on lever arm 48 to lift the member 43 and the detent 42 to free the ratchet bar. Subsequent forward movement of the lever arm 37 causes the idler slide 36 to advance with the pawl, which remains in engagement with the ratchet tooth thus advancing the ratchet bar. At the same time the pin 49 riding along the cam surface 44 retains the detent out of engagement with the ratchet bar. When the solenoid is deenergized, the initial backward movement of the lever arm 37 under the influence of the spring 40 causes the pawl to pivot on the idler slide 36 to lift the pawl out of engagement with the ratchet bar and causes the lever arm 49 to move downwardly allowing the member 43 and detent 42 to move downwardly to reengage the ratchet bar. Subsequent backward movement of the lever arm returns the slide 36 to its initial position.

In the embodiment illustrated in Figure 3 the pawl and detent are aligned to engage the same tooth of the ratchet bar, as this arrangement is frequently advantageous. It will be understood, however, that the pawl may be located either in front of or behind the detent, if desired.

It will be understood that the invention may be

variously modified and embodied within the scope of the subjoined claims.

I claim as my invention:

1. Ratchet mechanism comprising in combination, a ratchet provided with teeth movable along a fixed path, a pawl mounted upon an idler member for a first movement normal to said teeth for engagement and disengagement therewith and for a second movement with the idler member along a path parallel to that of the teeth for advancing the ratchet, a detent mounted for movement normal to said teeth for engagement and disengagement therewith for holding the ratchet except while it is being advanced, and interacting means between said pawl and detent for actuating the detent during the first movement of the pawl.

2. Ratchet mechanism comprising in combination, a ratchet provided with teeth movable along a fixed path, a pawl mounted upon an idler member for a first movement normal to said teeth for engagement and disengagement therewith and for a second movement with the idler member along a path parallel to that of the teeth for advancing the ratchet, a detent mounted for movement normal to said teeth for engagement and disengagement therewith for holding the ratchet except while it is being advanced, and interacting means between said pawl and detent for actuating the detent during the first movement of the pawl, said detent actuating means including a cam and cam follower having relative sliding movement during the ratchet advancing movement of said pawl.

3. Ratchet mechanism comprising in combination, a ratchet having an engageable feed element movable along a fixed path, a pawl mounted for movement parallel to the element path to advance the ratchet and pivoted for engaging movement relative to said element, a detent mounted for movement from and toward said element, a cam for moving said detent, said cam having a cam face parallel to said element path, and a member operated with said pawl for engaging the cam face to raise the detent during element engaging movement of the pawl and sliding along the cam face to hold the detent in raised position during advancing movement of the pawl.

4. Ratchet mechanism comprising in combination, a ratchet provided with teeth movable along a fixed path, an idler mounted for movement adjacent said ratchet, a pawl pivoted on said idler for a first or ratchet engaging and disengaging movement and a second or advancing and return movement, actuating means connected to said pawl to first engage and advance it and then raise and return it, a detent mounted for an engaging and disengaging movement relative to said ratchet teeth, and cam and cam follower means operatively arranged between said pawl and detent for raising the detent when the pawl is engaged, holding the detent raised as the pawl advances, dropping the detent when the pawl is reengaged, and leaving the detent down while the pawl returns.

5. Apparatus as set forth in claim 4, which further includes an element carried by said pawl for returning said idler when the pawl returns.

6. Apparatus as set forth in claim 4, which further includes a reversely acting pawl, idler, actuating means, and cam and cam follower means associated with said ratchet and detent.

7. Ratchet mechanism comprising in combination, a ratchet wheel, an idler coaxially mounted

alongside the wheel, a pawl pivoted on said idler, an arm on said pawl extending alongside an arm of said idler, actuating means connected to said pawl arm, a pin on said pawl arm for returning the idler with the pawl, a detent, a cam connected to the detent, and a cam operating arm on said pawl for first raising and then sliding along said cam.

8. Ratchet mechanism as set forth in claim 7, which further includes a reversely acting pawl, idler, actuating means, and cam and cam operating means associated with said ratchet and detent.

9. Ratchet mechanism as set forth in claim 7, which further includes a reversely acting pawl, idler, actuating means, and cam and cam operating means associated with said ratchet and detent, said actuating means for the two pawls including oppositely disposed power devices and a common return spring secured between the power devices.

10. Apparatus as set forth in claim 4 in which said ratchet and idler move rectilineally.

FRED WALLER.
